UNITED STATES PATENT OFFICE.

OSCAR J. TURNER, OF MINNEAPOLIS, MINNESOTA.

CAN-OPENER.

1,166,022.

Specification of Letters Patent.

Patented Dec. 28, 1915.

Application filed March 3, 1915. Serial No. 11,702.

To all whom it may concern:

Be it known that I, OSCAR J. TURNER, a citizen of the United States, residing at Minneapolis, in the county of Hennepin and 5 State of Minnesota, have invented certain new and useful Improvements in Can-Openers; and I do hereby declare the following to be a full, clear, and exact description of the invention, such as will enable 10 others skilled in the art to which it appertains to make and use the same.

My invention has for its object to provide an improved can opener; and, to this end, it consists of the novel devices and combinations of devices hereinafter described and defined in the claims.

In the accompanying drawings, which illustrate the invention, like characters indicate like parts throughout the several views.

20 Referring to the drawings: Figure 1 is a plan view of the improved can opener; Fig. 2 is a side elevation of the same; Fig. 3 is an end elevation of the same; Fig. 4 is a blank from which the improved can opener is 25 formed; Fig. 5 is a side elevation of the integrally formed knife blade and screw driver; and Fig. 6 is a transverse section taken near the end of the can opener and showing the tack puller.

30 The numeral 1 indicates a blank sheet of metal, cut to proper form, (see Fig. 4) which when bent upon itself affords a skeleton handle 2. Bent from one of the longitudinal edge portions of the blank 1, and at 35 the ends thereof, is a pair of outwardly and reversely extended bearing flanges 3. The other longitudinal edge portion of said blank is also bent to afford a pair of outwardly and reversely extended flanges 4 and 40 5, also located at the ends of said blank.

The longitudinal edge of the flange 4 is serrated to afford a fish scaler 6 and the longitudinal edge of the flange 5 is shaped to form a bottle crown remover 7. As shown, 45 the inner curved edge of the bottle crown remover 7 has a knife edge 8, for use in ripping sewed sacks. The can opener knife blade 9 is secured, by rivets 10, between the prongs of the handle 2 with its cutting edge 50 turned toward the operator and located substantially in the plane of the inner ends of the bearing flanges 3. Integrally formed with the knife blade 9 is a screw driver 11, which projects beyond the adjacent end of 55 the handle 1.

By reference to Fig. 2, it will be noted

that the bearing flanges 3 extend obliquely with respect to the adjacent longitudinal edge of the blank 1, so that when the knife blade 9 is forced through a can, to be 60 opened, and the bearing flanges 3 rest in flat engagement with the can, the handle 2 will extend upwardly toward the operator, thereby affording sufficient room for the operator's hand. Pivots secured between the 65 prongs of the handle 2, is a cork screw 12, adapted to be turned, from an inoperative position between the prongs of the handle, into an operative position, at right angles to said handle. Cut in the transverse portion 70 of the handle 2, is an aperture 13, having a contracted neck which affords a convenient tool for removing tacks and the like.

The can opener is especially designed to cut close to the edge of a can either on the 75 top or the side thereof and by arranging the knife blade as shown, with its cutting edge turned toward the operator cans may be opened with a very slight movement of the knife blade without disturbing the contents 80 of the can. This feature is highly important especially when salesmen are opening canned goods for display. The arrangement of the knife blade is such that in opening square cans the operator may cut 85 into the corners, thereby removing the entire cover.

Either one, or both, of the bearing flanges 3 may be used as a fulcrum for the knife blade 9, and, in some instances, and particularly in opening so called sanitary cans, the 90 screw driver 11 may be used as a fulcrum with its beveled edge following the folded edge of the can.

Among the many advantages of arranging the knife blade with its cutting edge toward the operator, may be mentioned that the operator's hand is always over the uncut portion of the can, thereby eliminating all danger of being cut by the ragged edge of 100 the can. It also makes it possible to guide the cutting edge of the knife blade by the back of the knife in engagement by the side of the can.

The above described can opener, while extremely simple and of small cost to manufacturers, is thought to be highly efficient for the purpose had in view.

What I claim is:—

1. In a can opener, the combination with 110 a blank strip of metal, bent upon itself to form a handle, one of the longitudinal edges

of said strip, at the ends thereof, being bent laterally to afford a pair of reversely extended bearing flanges, and a knife blade secured to said handle between said bearing flanges, with its cutting edge extended toward the operator and located at the inner ends of said bearing flanges.

2. In a can opener, the combination of a blank strip of metal bent upon itself to form a handle, one of the longitudinal edges of said strip, at the ends thereof, being bent laterally to afford a pair of reversely extended bearing flanges, and a knife blade having a fulcrum extension integrally

formed therewith, said knife blade being secured to said handle between its bearing flanges with its cutting edge turned toward the operator and located at the inner ends of said bearing flanges, and the said fulcrum extension projecting from the operator beyond the adjacent end of said handle. 15 20

In testimony whereof I affix my signature in presence of two witnesses.

OSCAR J. TURNER.
